UNITED STATES PATENT OFFICE

JOSEPH SENDELBACK AND ROY V. PALMER, OF McALESTER, OKLAHOMA

CLEANING COMPOSITION

No Drawing.

Application filed December 13, 1927. Serial No. 239,814.

Our invention relates to cleaning compositions, having particular reference to liquid compositions miscible with gasoline for the removal of grease, dirt and foreign matter 5 therefrom after the same has been employed as a cleaning agent for fabrics, clothing and the like.

Objects of the invention are: to provide a composition for cleaning and revivifying 10 gasoline after use in the cleaning of fabrics, clothing and the like; to provide a composition miscible with gasoline used as a cleaning agent, for washing the gasoline and precipitating grease, dirt and foreign matter 15 therefrom; to provide a composition of this character which is in itself a cleaning agent and which may be used in conjunction with gasoline, or alone if desired, for all 20 cleansing operations wherein gasoline may be used; and generally to provide a liquid composition for deodorizing, sweetening and strengthening gasoline used as a cleaning agent.

The ingredients, and proportions thereof, 25 herein disclosed, constitute the preferred embodiment in physical form of the principles of our invention, but it is to be understood that the specified proportions may be varied within reasonable limits without departing from the scope of the invention, such 30 variations depending upon conditions existing in materials cleaned.

The composition is prepared by dissolving and suspending, substantially in the following proportions, 8 ounces of caustic potash, 5 ounces of powdered commercial alum, and 2 ounces of oil of eucalyptus, in one gallon of alcohol, the concentration of which 40 may be varied to suit individual requirements.

In the preferred use of this composition it is mixed with gasoline which has been used as a cleaning agent, in variable proportions depending upon the exigencies of service. 45 The caustic potash gives heat, sweetens the gasoline, and facilitates hydrolysis. The alum congeals the grease, dirt and foreign matter. The oil of eucalyptus is a deodorant, and the alcohol forms a solvent and carrier 50 for the respective ingredients.

The solution of the above named ingredients is allowed to mix thoroughly with the dirty gasoline so that it may act upon and take up the grease, dirt and foreign matter, after which, being heavier than the gasoline, 55 it settles and precipitates the impure matter, leaving the gasoline free and in its initial state of purity.

It has been found that gasoline treated with this composition is not only cleansed but 60 is revivified and its cleansing properties enhanced. This is probably due to the fact that some alcohol and caustic potash, with probably slight quantities of the other ingredients, remain in solution and in suspension 65 in the gasoline.

In the use of the ingredients it has been found that the most effective variations in the respective proportions are from 5 to 8 ounces of the caustic potash, 3 to 5 ounces 70 of the alum, and 1 to 2 ounces of the oil of eucalyptus.

The composition is stable and in liquid form, retaining its effectiveness over a long period of time. 75

We claim:—

A cleaning composition consisting of substantially eight ounces of caustic potash dissolved in one gallon of alcohol and containing substantially two ounces of oil of eucalyptus, said solution carrying in suspension substantially five ounces of powdered alum. 80

In testimony whereof we affix our signatures.

JOSEPH SENDELBACK. 85
ROY V. PALMER.
